UNITED STATES PATENT OFFICE.

CLINTON F. SHADLE, OF INDIANAPOLIS, INDIANA, ASSIGNOR TO SHADLE AUTOMATIC TRAIN SIGNAL COMPANY.

SIGNAL SYSTEM FOR RAILWAYS.

1,397,883.

Specification of Letters Patent. Patented Nov. 22, 1921.

Application filed October 8, 1919. Serial No. 329,364.

To all whom it may concern:

Be it known that I, CLINTON F. SHADLE, a citizen of the United States, residing at Indianapolis, in the county of Marion and the 5 State of Indiana, have invented certain new and useful Improvements in Signal Systems for Railways, of which the following is a specification.

My invention is an improvement on the 10 signal system for railways shown, described and claimed in my copending application, Serial No. 249,554, filed August 12, 1918.

It is the object of my invention to provide means in a signal system for railways for 15 automatically making service application of the brakes when the block in advance is other than a clear block; further, to provide novel means in a signal system for railways for automatic service brake application of 20 the brake mechanism with gradual reduction of brake pipe air pressure by automatic action of the equalizing piston in the engineer's automatic brake valve following gradual automatic reduction of air pressure in 25 the equalizing reservoir to the air brake system, without movement of the engineer's brake valve, while the said valve is in normal running position. Further to provide 30 novel signal means for indicating each co-action between the traveling part and a local part; coaction between which results in automatic control in the traveling brake mechanism; further to provide traveling pick up mechanism influenced by a local control and 35 traveling maintaining mechanism amplifying the influence caused in said traveling pick-up mechanism; further to provide traveling retarding means arranged to retard the return to normal position for a fixed 40 period of time, of a traveling part after coaction of the traveling part with a local part; further to provide means in a signal system for railways for applying the brakes by automatic repetition of movement in the brake 45 applying means; further to provide means for manually interrupting said automatic movements; further to provide means automatically interrupting the supply of maintaining-air to the air brake mechanism; fur- 50 ther to provide means for manually controlling said last-named interruption; further to provide novel means for manual interruption of mechanism for controlling the automatic service brake application for per- 55 missive passing of the vehicle into a block

in unclear condition; further to provide air brake applying means including an equalizing piston and valve and automatic means for causing actuation of the latter; further to provide air-brake mechanism including 60 an equalizing piston and valve and automatic means and manually controlled means for interrupting supply of maintaining air acting on said valve; further to provide novel service application means for the 65 brakes; further to provide novel means for interrupting service application of the brakes; further to provide novel means of maintaining a permissive low speed control; further to provide a novel means of limited 70 speed control; further to provide novel means for indicating condition of the traveling mechanism; further to provide novel means for clear and caution conditions of the traveling devices; and further, to provide 75 novel local and traveling partial circuits and coactions therebetween for effecting signal indications on vehicle control.

The invention will be further readily understood from the following description and 80 claims, and from the drawings, in which the latter:

Figure 1 is a diagrammatic representation of the invention, the greater portion of the traveling mechanism being omitted. 85

Fig. 2 is a diagrammatic representation of the traveling portions of said exemplification.

Fig. 3 is a diagrammatic representation of the connections of the engineer's automatic brake valve with a portion of the traveling automatic control and actuating devices, the view being shown mainly in central vertical axial section, the handle of the engineer's automatic brake valve being 90 exemplified in running position. 95

Fig. 4 is a side elevation of the traveling contact shoe and the retarding means therefor.

Fig. 5 is a front elevation and cross section 100 of the maintaining circuit control switches and local pick-up circuit holding switch for clear and unclear conditions actuated by local contact with the ramp rail.

Fig. 5 (a) is a detailed drawing of the 105 roller bearing on the contact shoe shown in Fig. 4.

Fig. 5 (b) is a sectional view of the controller shown in Fig. 5.

Fig. 6 is an elevation and plan view of the 110

electric translating device for speed control and pick-up and maintaining control device, the electromagnets and circuit breakers being of same construction.

5 Fig. 6 (a) is a top view of the circuit controller shown in Fig. 6 and Fig. 6 (b) is a top view of the electromagnet shown immediately below Fig. 6.

Fig. 7 is a cross section of the speed control electro-magnet showing the two coils as wound on the magnet core. The winding for the pick up and maintaining electric translating devices are of the same construction with the exception that they have one 10 single winding with three binding posts, the center binding post tapped to a portion of the winding between two of the binding posts for low resistance and for quick action of armature, the two outside binding posts 15 cutting in the entire winding for the maintaining circuit.

Fig. 7 (a) is a diagrammatic view of the electromagnet shown in Fig. 7.

Fig. 8 shows a circuit breaker for the speed control circuit and is energized by a 25 circuit from the tachometer generator tapped across the mains between generator circuit leading to one of the windings of the two coil control magnet shown in Fig. 6 and 30 Fig. 7.

Fig. 9 is a front elevation of the tachometer generator from the pulley end showing the resilient steel belt as applied and driven from pony truck wheel.

35 Fig. 10 is a side elevation and partial cross section of tachometer generator.

Fig. 11 is an end elevation of a tachometer generator in cross section showing the construction of same and the armature slots 40 and commutators showing method of connecting the armature coils to the commutator bars.

Fig. 11 (a) shows the armature connections.

45 *The local control stations.*

The local control means may include signal mechanism, if desired, or the signal mechanism may be omitted. I have exemplified the local control means as including signal mechanism and as including the three 50 positions of the control and signaling mechanism, although if desired, the same may only be a clear position and an unclear position. (See Fig. 1).

11 and 12 represent the respective rails of a track which is divided into blocks of suitable lengths and suitable numbers four of these blocks being indicated at A, B, C and 60 D, separated by insulations 13. Both rails are in the present exemplification, shown as divided by said insulations.

B', C' and D' represent local stations at the entrance to the blocks B, C and D respectively. The parts of the respective lo-

cal stations have corresponding reference letters and numerals applied thereto. These local stations may be signal stations, but it is within the contemplation of my invention that these local stations may be used as 70 purely control stations for the traveling signal and control means, or signals of desirable character, number and location may be employed.

In the present exemplification the rail 11 75 is represented as the normally positive electric conducting rail for the polarity changing means exemplified in the local mechanism, and the rail 12 as the normally negative electric conducting rail of the latter. 80

At each local station there is preferably a local controlled means, shown as a semaphore arm 16 to accord with or indicate the condition of the block at the entrance to which the controlled means or signal is located. 85

In the present exemplification the semaphore arm at station B is in normal or upright position, the indicating light or spectacle 17 showing green, to indicate a clear or 90 proceed condition of block B; the semaphore arm at C is in slanting position, the indicating light or spectacle showing yellow to indicate a caution condition of block C; and the semaphore D is in horizontal 95 position, the indicating light or spectacle 19 showing red to indicate a danger condition of block D.

In the present exemplification, the local controlled means or controlled signals, when 100 signals are employed, are operated by compressed fluid, although it is within the scope of my invention to employ other means for operating the same. The compressed fluid is shown controlled by electrically operated 105 valves.

21 is a local control battery, which controls the electro-pneumatic valves 23, 24, communicating by passages 25, 26, with cylinders 27, 28, in which pistons 29, 30, operate. A piston-rod 31 extends from the piston 29 into the cylinder 28, and a piston-rod 32 is articulated with a lever 33 operating the local controlled means. The lever 33 is shown as pivoted on a pivot 34 in the 110 base of a suitable signal-mast, and articulated at 36 with an actuating rod 37 extending lengthwise of the signal-mast and articulated at 38 to the semaphore-arm, the latter being pivoted on a pivot 39 to the signal-mast. 115

A pipe 41 leads from a suitable source of compressed air to the inlet-port of the electro-pneumatic valve 23, and a pipe 42 leads from the passage 25 to the inlet-port 125 of electro-pneumatic valve 24, these inlet-ports being designated by the reference letter a. Each of the electro-pneumatic valves has an inlet valve b and an outlet valve c, the latter communicating with an outlet- 130

port *d* opening to the atmosphere. The valves *b* and *c* are connected by a stem *e* and are actuated by an electric translating device, represented as an electro-magnet, 5 these electro-magnets being designated 43 and 44, respectively. The electro-magnets normally cause opening of the inlet-valves and closing of the outlet-valves, as shown at station B, for depressing the pistons and 10 moving the signal into green or clear positions.

When the compressed fluid is shut off from cylinder 28 and said cylinder is opened by the breaking of the circuit of magnet 15 44, the weight of the semaphore-arm, in the present exemplification of the controlled means, causes retraction of the piston 30 until it strikes the piston-rod 31, which is held by the pressure on its 20 piston, bringing the signal to the yellow or caution position shown in station C'.

When the circuit of electro-magnet 43 is interrupted, compressed fluid will also be shut off from cylinder 27 and said cylinder 25 opened to the atmosphere, allowing retraction of both pistons and causing the semaphore-arm, in the present exemplification, to descend by gravity, placing the controlled or signaling means in red or danger position, as shown at station D'.

The armatures of electro-magnets 43, 44, are actuated through the medium of the local 30 control battery 21. Electric conductors 46, 47, having a circuit-interrupter 48 therein, 35 connect one of the poles of the battery 21 with one of the terminals of electro-magnet 43, and an electric conductor 49 connects the other pole of the battery 21 with the other terminal of the magnet 43. Electric conductors 46, 53, having a circuit-interrupter 40 54 therein, connect one of the poles of the battery 21 with one of the terminals of the electro-magnet 44, and electric conductors 49, 55, connect the other pole of said battery 45 with the other terminal of said electro-magnet 44.

The circuit-interrupters 48, 54, are controlled from an advance local station, preferably from the station at the entrance to the 50 next block in advance. Thus the said circuit-interrupters at station B' are controlled from the local station C' through the medium of a track circuit, the circuit-interrupters at local station C' being controlled 55 from the local station D' through the medium of a similar track circuit.

A track battery is shown at 61. A pole-changer, represented as a mechanical pole-changer 62, is interposed between said battery and the track. The pole-changer is represented as having contact-arms 63, 64, connected by an insulated bar 65 and arranged to coöperate with contacts 66, 67 and 68. One of the arms is articulated at 69 with the 60 signal-rod 37. The contacts 66, 68, are con- 65

nected by electric conductors 70 with the negative pole of the track battery, while the contact 67 is connected by an electric conductor 71 with the positive pole of the track battery. An electric conductor 72 connects 70 the arm 63 with the rail 11 of the block in rear of the one at the entrance to which the local signal is located, and an electric conductor 73 connects the arm 64 with the rail 12 of said block. 75

The circuit-interrupters 48, 54, of the local station at the entrance of the block with which the electric conductors 72, 73, connect, are controlled by a local electric translating device or electric value selector, 80 hereinafter referred to as a polarity selector, shown as a relay 74, energized by the track battery of said block. An electric conductor 75 connects the rail 11 of said block with one of the terminals of said relay, and an 85 electric conductor 76 connects the rail 12 of said block with the other terminal of said relay. Said relay is preferably a polarized relay, comprising a polarized armature forming the circuit-interrupter 54, and a 90 neutral armature forming the circuit-interrupter 48.

When now the local controlled part or signal is in clear or green position, as shown at local station B', which is the local station 95 for the block in advance B', the local pole changer 62 will be in such position that the positive pole of the track battery at said local station will have connection with the right hand or normally positive rail of the 100 block in rear A, and the negative pole of the track-battery will have connection with the left hand or normally negative rail of said block in rear A, for energizing the local polarized relay or polarity selector 74 at the 105 entrance of said block, and causing a current therethrough in accord with the position of the local pole-changer 62 at local station B', and closing the circuit-interrupters in the electro-pneumatic valve circuits at the entrance of said block A in the 110 absence of a vehicle or other obstruction or derangement in said block.

The presence of a vehicle in said block A, indicated at W, will, however, short circuit 115 the track-battery across said rails through the wheels and axles of the vehicle, and take the current from said local polarized relay and thereby open said circuit-interrupter 48, which is a neutral armature, causing the controlled device or signal at the entrance to block A to go to danger or red, a relation shown at local station D', the circuit-interrupter 54 having been previously swung for yellow or caution condition of block. 120

This relation changes the poles in the pole-changer 62 at local station D' so as to connect the right-hand of block C, looking in the proceed direction, indicated by the arrow *g*, with the negative pole of the track-battery 125 130

61 at station D' thereby reversing the polarity of the polarized relay 74 at station C', and causing a swinging of the circuit-interrupter 54, which is a polarized armature, so 5 as to break the circuit energizing the coil of electro-pneumatic valve 24 at station C', and cause the controlled device or signal at said station C' to move to caution or yellow position.

10 Electric connections are further made with the local control battery 21 shown as a signal battery, continued into a different block, for instance, a block in the rear, where local electric transferring or influencing 15 means for the same are provided, exemplified as comprising the track rail or rails and a ramp-rail, acting as contacts, and forming a normally interrupted or partial circuit. These electric connections include an electric 20 transferring or influencing means exemplified as a circuit interrupting mechanism arranged for conveying the influence of the local electric signaling or controlled means to the traveling mechanism for influencing 25 the latter, when the block being approached is a clear or green block, or interrupting said electric transferring or influencing means, when the block being approached is not a clear block, so as to indicate on the traveling 30 vehicle whether the block which is being approached is clear or other than clear. The local circuit-interrupter as exemplified is a polarized relay 74 energized by the track battery as before described, comprising a 35 polarized armature forming the circuit interrupter means 54, electric connection with the positive pole of the local control battery 21, as by being connected with electric conductor 46, through circuit interrupter 48, 40 electric conductor 53, electric conductor 89, and extends lengthwise of the track a suitable distance and connects with a local electric influencing or transferring device represented as local contacts 90, and shown as 45 ramp-rails. This local contact is projected a sufficient distance in the rear of the block which it serves, so that the driver of an on-coming vehicle may have information in his traveling mechanism, and if desired automatic control operation therein, in advance 50 of the time of the arrival of the vehicle at the block in advance served by said local contact. The two ramp rails are connected in multiple for the purpose of the engine running either forward or backward, or for 55 single track movement in both directions.

An electric conductor 91 connects with electric conductor 50 and negative pole of local battery and is shown connected with 60 the rail 12 of the block in rear and as extending lengthwise of the track a suitable distance to a point opposite the local contact 90.

In the present exemplification, the local electric transferring devices are local contacts, one of which is a local contact rail or

ramp-rail insulated from the traffic rails. The ramp rails may be of suitable length, the length being determined by the probable speed of the vehicles passing therealong and the sensitiveness of the electrical devices co- 70 acting therewith. I have provided means, however, whereby the ramp-rail may be shortened and the length of time of coacting between the traveling contact and the local contact may be materially reduced as will be 75 described.

The local contact which acts to effect change in relation in the traveling mechanism is preferably placed at a suitable distance from the block at the entrance to which 80 the local station from which its electric conductor extends, this distance determining the length of time of travel throughout which the driver of the oncoming vehicle will have advance information of the state of the controlled means or of the signal, if a signal is employed, at the local station which he is 85 approaching.

The local signal mechanism may, if desired, be omitted, and a signal light as an 90 indicator substituted.

In the present exemplification of my invention, when the block in advance is in clear or green condition, as exemplified by the block B, the relay armatures 48 and 54 95 are closed, whereby a local interrupted circuit from the local control battery is formed, this local interrupted circuit having as its terminals the track 11 and the local contact 90, so that, when the traveling contacts, ex- 100 exemplified as the wheels and axle of the vehicle and a shoe on the vehicle, as hereafter explained, coat with the track rail and the local contact, the said interrupted local circuit including the local control service of 105 electric energy, is closed through a traveling partial circuit including an electric transferring, influencing or translating device on the vehicle, to transmit the influence of said local control battery to the traveling mechanism, as hereinafter more fully explained. When, however, the circuit interrupter 53 is 110 open, the said local partial circuit is interrupted, which interruption occurs when the local control means for the block in advance 115 is either in caution or in danger condition, with the result that no electric influence is conveyed to the local contacts serving said block to close said traveling partial circuit.

In the present exemplification of the invention, the traveling mechanism embodies automatic pick-up mechanism for picking up in the traveling mechanism the condition of the block in advance, and automatic maintaining mechanism for maintaining the 125 pick-up condition so as to prolong the pick-up effect resulting from coacting between the traveling electric transferring or influencing device.

The automatic pick-up and maintaining 130

mechanism is exemplified as including a shoe and a retarding means for automatically retarding the return to normal position of the shoe on leaving the ramp. I 5 prefer that the action of the shoe and retarding means in the pick-up function shall be concurrent. I employ the time during which the shoe mechanism is returning to the normal position to effect the circuit controlling the clear and unclear conditions of 10 the signal and brake control means causing sequential action in those means in manner to be hereinafter described.

The invention is not limited to the brake means shown and described, it being obvious that other means and other connections than those shown and described may be employed without departing from the spirit of the invention; and further, that parts of 15 the mechanism may be employed without employing other parts, and that parts may be substituted for the parts not employed, within the scope of the appended claims.

20 *The traveling pick-up and maintaining means.*

The vehicle is provided with traveling electric influencing or transferring devices, shown as a shoe 101 coacting with the local 25 contact or ramp-rail 90 and as the wheels and axles 102 of the vehicle coacting with the rails 11, 12 or with both said rails, (see Figs. 1 and 2). These traveling contacts represent the terminals of a traveling partial circuit in which a traveling electric 30 translating device 103 is included. This traveling partial circuit includes the shoe 101, an electric conductor 108 in which a terminal 107 is included, the electric translating device 103, and electric conductors 130, 131, 132, 109, grounded on the engine frame and shown as leading to the wheels and axle 102. When now the traveling vehicle is, as exemplified in Fig. 1, traveling 35 in the proceed direction, shown by the arrow in Fig. 1; and the traveling contact 101 makes contact with the local contact 90, the traveling contact 102 being in contact with the local contacts 11, 12, or track rails, the relay armature 54, being closed by reason of the clear or green signal condition of the block in advance B, the local partial circuit from the local control electric source of energy shown as the battery 21 is closed 40 through the traveling partial circuit just described for influencing the electric translating device 103, in this instance energizing the same, and thereby influencing the traveling signal and control mechanisms for a 45 clear or green light relation of the latter.

If, however, the vehicle is proceeding in block B, the coacting relation occurs in said block between the traveling contact and the local contact, and the relay armature contact 54 being open, the said local control

battery 21, therefore will fail to have influence on the traveling partial circuit, whereby the electric translating device 103 on the vehicle will remain unaffected, the result being that the traveling signaling and control means will be in a negative condition or relation to indicate an unclear condition of the block in advance for causing the signaling and control relations hereinafter described. 70

An unclear condition in the traveling signaling and control means will also be present when the traveling contact makes contact with the local contact projected in advance from a danger or red block D' as the 80 said contact 54 of relay will in that condition of the block signaling means also be open for interrupting the local partial circuit.

The normal deenergized condition of the 85 electric translating device 103 is a check against false indication, for if there is no energizing of this electric translating device on a pickup, owing to defect in the circuit, the control system goes to caution even 90 if the block in advance is a clear block.

In the present exemplification of the invention, the traveling mechanism embodies means whereby the contact or influencing effect of coaction between the traveling electric influencing or transferring means or contact, and the local electric influencing or transferring means or contact, is prolonged, so that when, for instance, a ramp-rail is employed, a comparatively short ramp-rail 100 will suffice to transfer the influence of the local source of electric energy to the part of the traveling mechanism influenced thereby. The picked up or influenced position in the traveling partial circuit is arranged 105 to be maintained by a traveling maintaining circuit which includes the electric translating device of the pick-up mechanism.

The traveling maintaining circuit is shown as comprising a traveling source of electric 110 energy, (see Fig. 2) exemplified as a traveling battery 121, an electric conductor 122 leading from the positive pole of the traveling battery, an electric conductor 123 connecting the latter with a switch 124, electric 115 conductors 125, connecting the latter with a switch 126, an electric conductor 129 having connection with one terminal of the electric translating device 103, an electric conductor 130, having connection with the other terminal of the latter, and electric conductors 131, 132, 133, connecting with the negative pole of the traveling battery. The traveling source of electric energy may be any traveling electricity generating device to impart electric energy to the traveling mechanism. 120

The actuation of the shoe or traveling contact causes closing of the switch 124, in a manner to be presently described, and the 130

energizing of the electric translating device 103, by coaction between the traveling contact and the local contact, causes closing of the switch 126, whereby the circuit from the traveling source of electric energy through said electric translating device 103 is completed.

The electric translating device 103, therefore, substantially simultaneously, receives current from the local source of electric energy and from the traveling source of electric energy, which condition, however, endures but for a short interval, being practically only momentary, the circuits, however, being in multiple with the same terminal of the electric translating device 103 is connected with the negative poles of the local battery and of the traveling battery.

The influence of the local battery on the electric translating device 103 is only momentary and may be described as a pick-up influence thereon, whereas the influence of the traveling battery on the electric translating device 103 is prolonged and may be shown as a maintaining circuit, which has the effect of permitting a very short local contact to be employed for causing setting-up influence in the electric translating device 103, which set-up is maintained by the traveling source of electric energy after the traveling contact has left the local contact, in order to maintain said electric translating device 103 and the parts actuated thereby in set-up relation, so that the various actuations or changes in positions in the traveling signal mechanism and the traveling control mechanism may take place in the desired manner prior to the cessation of maintaining influence on said electric translating device.

I have exemplified such means as comprising retarding means for retarding the cessation of the influence caused by the coaction of the traveling contact with the local contact, and shown as means for retarding the breaking of the maintaining circuit of the traveling battery.

The retarding means is shown as connected with the traveling contact or shoe. This means is exemplified as consisting of the following instrumentalities (see Figs. 4 and 5).

The shoe 101 is exemplified as comprising a contact-plate extending lengthwise of the direction of travel, the ends of the contact plate being provided with lugs 142, the respective ends of the contact plate are articulated at 144 with links 144 articulated at 145 with anchor plates 146, secured in suitable manner to a beam secured to the running gear of the vehicle insulated therefrom as by insulation 147 and 148. One end of the conductor 108 is secured to the contact plate, as by lug 149 for receiving electric

current from the local contact. The stem 154 is insulated from the shoe by insulation 148. A stem is arranged to reciprocate in a bearing 155 of the beam the movement in one direction being caused by the movement of the shoe. When the shoe makes contact with the ramp-rail, it is raised by the ramp-rail, the ends of the ramp-rail sloping as shown at 156 for avoiding abrupt end-contact between the shoe and ramp-rail. The stem 154 is provided with a cap and jaw 157 for connection to crank arm 158 fixed at one end by bearing 170 for operating switches 124, 127 and 128 through rotary movement of switches.

A spring 159 located between bearing 155 and a flange 160 on the stem normally causes return of the stem when the shoe leaves the local contact, the spring 159 returning the shoe and rotary switches to normal position. The stem 154 also has a socket stem 157 with 85 jaw provided with spring 161. The movement of socket stem 157 is limited by pin 162 through slot 163 the pin 162 passing through and fixed to stem 157. A stop 164 is provided for limiting the movement of 90 stem and jaw 157; the function of the stop 164 is to limit the travel of crank arm 158 and movement of switches 124, 127 and 128. The stem 154 may therefore have a greater movement than stem 157 caused by varying 95 heights of alignment of ramp rail, or adjustment of shoe on the vehicle.

A retarding means exemplified as a cylinder 165 and piston 166 therein, from which a piston rod 167 extends, is acted on by the crank arm 158 operating rotary switches 124, 127, 128, the switches 127 and 128 exemplified as normally closed switches, and switch 124 as a normally open switch, switches 124A, 124B, as normally closed 105 switches forming a shunting circuit from 124A across contact plate 124B through electric conductor 125, through electric circuit contacts 126, through electric conductor 129, through winding on electric translating 110 device 103, through electric conductor 130, through electric conductor 131, connecting with contact 124A, across plate 124B, forming a shunt to provide against electric translating device 103 failing to release caused 115 by static electricity in the fields or grounded circuit sufficient to hold the electric translating device 103 in closed relation after the shoe leaves the ramp and the circuit controllers 124 and 124A have returned to the 120 normal relation of contact roller F. The piston rod is provided with adjustable jaw 168 for connecting to crank arm 158. The actuation of the stem 154 by means of the shoe on contact with the local ramp-rail is 125 instantaneous for operating the rotary switches, but the return of the stem upon the shoe leaving the ramp-rail is retarded by

- means of the retarding dash pot 165. For 5 accomplishing this I have shown the piston as provided with ports 181 a valve 182 is movable lengthwise of the piston-rod, the face of the valve being provided with a washer 183, and a collar 184 threaded to the piston-rod between the valve and the collar acting to normally close said ports and for adjusting to prolong or reduce time of 10 return of the piston 166, stem 167 to normal or retracted position. This return is a retarded return, the cylinder preferably contains a liquid, such as a light oil, indicated at A.
- 15 The spring 159 acts to normally return the stem 154, switches 124, 127, 128 and piston and valve to normal or retracted position. The movement of the piston in the cylinder, when a ramp rail is contacted, is rapid, the 20 stem 154 and crank arm 158 acting to raise the piston with a quick movement. The weight and compression of the fluid above the valve 182 causes the valve to recede from the ports for opening said ports, so that the 25 oil may readily pass through said ports. When now the shoe leaves the ramp-rail the stem is urged by means of the springs 159 and 161. This return is however a retarded return, owing to the fact that the ports 181 30 are closed. The return of the piston is against the resistance of the oil or liquid in the cylinder under the piston, for permitting the return. The valve is provided with a metal washer 183 and collar 184 to limit the 35 passage of the liquid through opening in the valve to the upper end of the cylinder above the piston, the metal washer acting as a valve seat with which the valve coacts. The latter is shown adjustable, as by providing 40 the stem with a threaded connection with the piston rod, the stem passing through a bore in the piston-rod and having leak proof connection with the wall thereof. The adjustment of the valve determines the 45 rapidity of return of the rod and the duration of the closed condition of the switches and is useful, especially when employing the retarding means on trains of different speeds.
- 50 The leaf springs forming the switches are shown secured in the casing. The shoe acts on switch 128 for making and breaking the circuit in an electric translating device 212 which acts in sequence with the electric 55 translating device for controlling the clear and unclear condition of the traveling mechanism, in manner to be presently explained.

The traveling signal and control means.

- 60 The vehicle is provided with a traveling electric influencing or transferring device shown as traveling contacts 101, 102, coöperating with the respective local contacts of the blocks. The traveling contact shoe coacting

with the local contact or ramp rail 90, while 65 the traveling contact 102 is shown as the frame, axle and wheel of the vehicle. A traveling electric translating or transferring device 103 hereinafter termed a traveling translating device is arranged to have electric 70 connection with said traveling contacts 101, 102 for being brought into accord with the local electric translating device or control means of the local station at the entrance of the block in advance of the position of the vehicle.

In the present exemplification of the invention, the traveling mechanism embodies automatic signal mechanism for indicating the condition of the block in advance; 80 the automatic application of the service brakes in the event such block is other than clear. Automatic speed control mechanism arranged for permissive running in a given block and automatic signal mechanism and 85 automatic indicating mechanism acting during passage by the vehicle of a local contact to indicate such passage.

The invention is not limited to the particular means shown and described, it being 90 obvious that other means and other connections than those shown and described may be employed without departing from the spirit of the invention.

The traveling signal and control mechanisms include a series of automatically actuated devices which are shown in the present exemplification. Thus 103 is an automatic pick up device actuated by coaction of the shoe and local ramp rail contact for 100 clear condition of block in advance, and 212 is an automatic maintaining brake control device for clear condition of block; 223 is an automatic service brake application device; 224 is an automatic maintaining air 105 device, both of said last named devices being controlled by the maintaining brake control device 212. The actuating means of said devices are exemplified as electro-pneumatic valves and electromagnet translating devices. (See Figs. 2, 3, 6 and 7.) The traveling translating devices 103 and 212 are shown as iron clad electromagnets. These magnets have a low resistance for the pick-up circuit and a high resistance for the 110 maintaining circuit.

The electromagnet translating device 103 is arranged to actuate the translating device 212 for clear conditions; the magnet coil 212 is energized for maintaining the traveling 120 signal and the traveling automatic brake control mechanism for clear condition of the block ahead, and is deenergized for caution and danger condition of block ahead and acts to release automatic brake control 125 devices for service application of the brake mechanism.

Electro-pneumatic valve 232 of the service

brake application device 223 is controlled by the maintaining device 212, electric translating device 233 is continuously energized for clear condition of the block, and de-
5 energized for caution and danger condition of block and produces an automatic service application of the brake mechanism; an electro-pneumatic valve 235 of the maintaining air device 224 has its electric translating device 236 energized for clear condition of the block and deenergized for caution condition and danger condition of block, the control of said electro-pneumatic valves transferred to a permissive low speed
10 control means for the last named condition of block.

This latter electro-pneumatic valve acts, when its electric translating device is energized, to maintain a compressed air valve
20 238 of the maintaining air device 224 which it controls, open during energized condition of its electric translating device, and closed during deenergized condition of the electric translating device, whereas the electro-pneumatic valve 232 is arranged to maintain the pneumatic valve 239 which it controls closed during energized condition of the electric translating device of the said electro-pneumatic valve, and the pneumatic valve open
25 during deenergized condition of the electric translating device.

The positive pole of the traveling battery is preferably connected by electric conductors with all of the traveling control instruments, whereas in practice the negative pole of the traveling battery may be connected with the engine frame and the negative side of the traveling control instruments may be similarly connected with the
30 engine frame. I have, however, in the drawings, shown the circuits completed by wire conductors.

The traveling electro-pneumatic valves mentioned, which may be alike, have an inlet valve *i* urged to seating position by a spring *k* and an outlet valve *l*, the latter communicating with an outlet port *m* opening to the atmosphere (see Fig. 3). The valves *i* and *l* are connected by a stem *n*, and
45 are actuated by the electric translating devices represented as electromagnets, of said respective electro-pneumatic valves, the armatures of which connect with said stem. The amount of air required to operate the
50 controlled parts by means of these valves is small, and will not affect the air-brake system.

The electro-pneumatic valves 232 and 235 are fed from a suitable source of compressed air as from the usual main reservoir 241 of the locomotive which feeds the usual air brake system. (See Figs. 2 and 3).

A pipe 242 connects with the main reservoir, a branch pipe 243 connects with the inlet port of electro-pneumatic valve 232, and

pipe 245 connects with the inlet port of electro-pneumatic valve 235.

Indicating condition of traveling mechanism.

The stem 154 of the traveling contact 101 70 is provided with a crank arm 158 for actuating switches 124, 124A, 124B, 127, 128, 128A and 128B, located in housing C. The switch fingers are mounted on fiber insulator blocks D and E a roller of fiber F is rotated for 75 bringing into contact metal contact plates mounted on the roller to complete an electric circuit through the switch fingers, the switches being in open or closed position according to the position of the roller plates 80 actuated by the stem 154, lever 158 and link 150a of the contact shoe.

When the traveling shoe is raised upon making contact with the local ramp-rail, the roller plates are moved around the spring 85 fingers opening switches 127, 128 normally in closed position for completing certain electric circuits, whereas switch 124 is in normal open position; switches 124A and 124B are normally closed across contact plates and 90 switches 128A and 128B are closed across roller plate (see Fig. 2). Switches 124A, 124B, 128A, 128B when closed across roller plates form a shunt across the terminals of electric translating devices 103 and 212 for the purpose of cross circuit protection, and only come
95 into contact following the opening or breaking of the maintaining energizing circuit of the electric translating devices 103 and 212, and at the closing of the shunt circuit across the switch fingers and contact plates will discharge any static electricity contained in the fields of the electromagnets of devices 103 and 212 and compel the release of the electromagnet armatures assisted to open position 100 by the springs 48; the shunt circuit is also for the purpose, as before stated, of preventing stray electric currents from partially grounded wires should they exist from holding the electromagnets in closed relation after the maintaining circuits have been opened by the movement of the switches in the said circuits. When the switch 128 is opened by upward movement of the shoe de-energizing the electric translating device 105 212 for causing opening of switches 208, 215, at the same time the reverse from normal movement of the roller, the switch 128 is closed through the roller contact 128B to 128A thus placing a shunt circuit across the 110 terminals of translating device 212 for the purpose of discharging any static electricity in the electromagnetic field that would have the tendency to hold the armature 41 from a quick release occasioned by static electricity 115 and further as a protection from stray electric currents from an electric conductor that could result from poor insulation; in other words, the closed or shunt circuit is for the purpose of cross circuit protection.

130

The deenergizing of translating device 212 breaks its maintaining electric circuit at switch 215 to the negative pole of the traveling battery which is as shown a stick circuit, therefore the translating device 212 and switches 208, 215 will remain in open position after the traveling contact 101 returns to normal position after passing over the local contact or ramp-rail, providing the block entered is other than a clear block. The parts are in such position that, when the traveling shoe 101 coacts with the ramp-rail 90, the translating device 103 is energized when the block in advance is a clear block. Then, when the traveling shoe leaves the ramp rail whereby the rotary switch is again closed, completing the electric circuit through translating device 212 in a circuit comprising the positive electric conductors 122, 140, 200, switch 128, electric conductor 201, the electric translating device 212 through low resistance tap of winding and the conductor 202, switch 203, electric conductor 204, electric conductors 205, 131, 132, and the common negative electric conductor 133, thus energizes the translating device 212 and actuates its armature and switches 208 and 215. Then the circuit common negative pole of the traveling battery is made from electric conductor 201 through the entire winding of the translating device 212, electric conductor 310, switch 215 and electric conductors 311 and 29 to the negative pole of the traveling battery. Switch 128 closes the electric circuit before the holding circuit of the electric translating device 103 is opened at switch 124 by reason of the advanced position of contact on roller of switch 128. As hereinbefore stated, the return rotary movement of the switch to normal position after contact shoe leaves the ramp rail is slow, being retarded to return movement by the dash pot.

There is no action of the automatic electro-pneumatic service brake valve 223 or the automatic electro-pneumatic maintaining air valve 224 following the deenergizing of translating device 212 and breaking of the partial maintaining circuit at switch 208. When the block in advance is in a clear condition, the electric pick up translating device 103 is energized at the moment of the coaction of the traveling contact shoe 101 with the ramp-rail 90 preceding the deenergizing of the translating device 212, the closing of switch 312 is actuated by electric translating device 103 thereby closing the positive pole of the traveling battery by electric conductors 122, 140, 141, 207, 308, switch 312, electric conductor 309, tapping electric conductor 209 thus completing the maintaining circuit and maintaining the automatic brake mechanism in closed position while the transference of electrical energy from the ramp-rail 90 to the traveling contact shoe may be late in action following co-

action, the relation is, however, only momentary, and the partial maintaining circuit of the electro-pneumatic valves of the brake mechanism will again be energized.

Prior to the resultant effects on the electro-pneumatic valves 232, 235, and the actuation of the parts controlled thereby, the deenergizing of translating device 212 is followed by the closing of switch 208 on back point for causing a visual signal, represented as an electric light bulb B with yellow spectacle to appear, the circuit for the same being through the common positive electric conductors 122, 140, 141, 207, switch 208, electric conductor 213A, and electric light bulb B and electric conductors 214, 205, 131, 132 to the common negative conductor 133. The electric pick up translating device 103 actuates switches 126, 203 and 312 and is actuated only during the period of coaction of the traveling contact shoe 101 with the local contact ramp-rail 90. When the block in advance is in a clear condition, by energizing the electric circuit comprising the traveling shoe 101, circuit through link 144, anchor plates, bolt and lug 107, an electric conductor 108 to the low resistance terminal of winding of translating device 103 to electric conductors 130, 131, 132 and electric conductor 109 and tap 102 on engine frame, the circuit is completed through axle and wheels of vehicle through running rail to negative pole of local station battery 21. This is designated as the pick up circuit. For a clear block in advance, the actuating of the armature of electric translating device 103 closes switches 126, 203 and 312 at the same time the coaction between the traveling contact and the local contact also operates rotary switch contacts located in housing C (see Fig. 5) and breaking the shunt circuit at contact 124B and the closing of switch 124 completing a stick circuit through translating device 103, comprised of electric conductor 122 from the common positive pole of the traveling battery, electric conductor 123, switch 124, an electric conductor 125, a switch 126, an electric conductor 129, to terminal of the translating device 103 through entire coil of high resistance to terminal and electric conductors 130, 131, 132 and 133 to common negative pole of the traveling battery, this circuit shown as the stick and holding circuit and is for the purpose of insuring a set up position or translating device 212, heretofore described. Should the electrical contact between the traveling shoe and the local contact be only for a fraction of the length of the local contact it will be sufficient to energize electric translating device 103, the stick circuit will maintain the said translating device in energized condition.

The coaction between the traveling contact and the local contact and closing switch 130

124, also sounds an audible signal (see Fig. 2). This audible signal is exemplified as an electrically actuated horn K, such as a Klaxon horn, the armature-coil whereof is energized from the traveling battery by a circuit comprising the common positive electric conductors 122, 123, the switch 124, electric conductor 125 electric conductor 125A, the electric translating device of the horn, an electric conductor 125B, 214, 205, 131, 132 and 133 to the common negative pole of the traveling battery.

The traveling mechanism having been set up for clear condition or green condition of block ahead, the vehicle automatically proceeds at speed after the indications have been received, and indicates to the engineer or driver the fact of coaction between a traveling contact and a local contact. The audible indication is by means of the horn and the visual indication is by means of the appearance of the yellow light.

Unclear condition of traveling mechanism.

Assuming now that the vehicle is traveling in block "B" and approaching the local electric transferring means projected in rear from the local control station "C" which is set up for caution condition of block ahead, the local electric transferring means thereof will be in deenergized condition, due to the open relation of the polarized armature 54 of the track relay 74. The traveling partial circuit in which the electric pick up translating device 103 is located will, therefore, fail to receive energizing influence from the local partial circuit, and said electric translating device 103 will remain deenergized whereby the switches 126, 203 and 312 remain open. The switches 127, 128 will also be opened and switch 124 will be closed by the movement of the traveling shoe 101 whereby the electric translating device 212 is deenergized and the winding shunted, thereby opening the switches 215, 208 whereby the green light "A" is extinguished and the yellow light B appears by reason of the back contact of the switch 208 with electric conductor 213A closing the circuit through yellow light bulb B. The audible signal K namely the horn will also sound.

The opening of switch 208 front contact thereby breaking the circuit controlling the automatic maintaining air valve 238 and the automatic service brake valve 239 whereby the deenergizing of the electric translating devices 233 and 236 causes closing of the electro-pneumatic valves 232 and 235 and the release of air pressure against the pistons 401 and 414 thereof through the exit ports m whereby the maintaining air valve 238 is closed for automatically shutting off the maintaining air from the brake system and the opening of the air valve 239 for a service application of the brakes by causing de-

crease in pressure in the equalizing reservoir, and relief of air pressure in chamber on top of equalizing piston in engineer's automatic brake valve, the raising of piston by pressure under said piston from the brake pipe and opening of its valve allowing the brake pipe air to flow to the atmosphere thus making a gradual brake pipe reduction.

The deenergizing of the electric translating device 233 acts to open the air brake valve 239. This valve connects with a pipe 395 which has suitable connections for releasing pressure in the train brake pipe 450 for applying the brakes (see Figs. 2 and 3). This release of pressure is controlled by an adjustable automatic intermittent air release valve 396 (see Fig. 3) which releases the air to the atmosphere, so that a gradual release of pressure of say ten, fifteen or twenty pounds per square inch, as desired, is obtained at each opening of the valve 239 dependent on the amount of normal pressure in equalizing reservoir and train brake pipe, for instance ninety pounds or one hundred and ten pounds, and as stated, the determined speed and weight of the train, and the desired distance within which it is desired to stop the same. For instance, on a heavy high speed train which it is desired to bring to a quick stop, each brake pipe reduction in case it is a passenger train, may be from twenty to twenty-five pounds.

Actuation of the valve 239 is accomplished by a piston 401 connected therewith by a piston-rod 402 and reciprocable in a cylinder 403, with which the inlet-valve i and the outlet-valve l of electro-pneumatic valve 232 is connected by a passage 404. The area of piston 401 is greater than the area of valve 239, and the pressure in pipe 243 is in practice greater than the pressure in pipe 395.

The automatic intermittent air release valve as indicated by character 396 (see Fig. 3) which is a sectional view of the valve and casing which is an essential part of the valve. It is unlike a safety pop valve, as its construction is such as to cause it to close quickly with a pop action, insuring its seating firmly. It is sensitive in operation. The valve 500 is held to its seat by the compression of spring 501, between the flange of the stem and adjusting nut 502. When the air pressure below valve 500 is greater than the force exerted by the spring 501 it rises and as a larger area is then exposed, its movement upward is very quick, being guided by the brass bush in the body 503. Two ports are drilled in this bush upward to the spring chamber; and two outward through the body to the atmosphere. As the valve moves upward its lift is determined by the stem 505 striking cap nut 506. It closes the two vertical ports in the bush connecting the valve and spring chambers, and opens the lower ports to the atmosphere. As the air

pressure below valve 500 decreases and the compression of the spring forces the stem and valve downward, the valve restricts the lower ports to the atmosphere and opens 5 those between the valve and spring chambers. The discharge air pressure then has access to the spring chamber. This chamber is always connected to the atmosphere by two small holes through the body 503; the 10 air from the valve chamber enters more rapidly than it can escape through these holes, causing pressure to accumulate above the valve and assist the spring to close it with the pop action before mentioned. The valve 15 is adjusted by removing cap nut 506 and screwing up or down the adjusting nut 502. The size of the exhaust ports are very important and cannot be changed in size. The valve can be accurately adjusted to release 20 at any pressure from 50 pounds to 125 pounds and in action will pop off and make a gradual release of air pressure. If adjusted to release twenty pounds from the equalizing reservoir of the brake system the valve will 25 pop off accurately the twenty pounds and firmly reseat the valve. The pop action is desirable as the air pressure from the equalizing reservoir is graduated off and assists the equalizing piston 457 to come into action 30 for making a gradual brake pipe reduction through the engineer's automatic brake valve, approximating the manual operation of the engineer's automatic brake valve when operated for a service brake applica- 35

The pop action of the automatic intermittent air release valve is to cause the graduated piston 457 in engineer's automatic brake valve to make the reduction from the 40 brake pipe in two applications; the air pressure from brake pipe 450 causes this action. On the quick opening of valve 239 air pressure flows freely through one-inch pipe 504 to hand release cylinder 302; the one-inch 45 pipe 504 is several feet in length for the purpose of actuating hand release 302 circuit breaker 95, and the air released to one-inch pipe freely affords a quick release of air pressure from the equalizing reservoir, and 50 immediate action of the equalizing piston 457. The air cannot exhaust to atmosphere through hand release 302 and as pressure builds up, the intermittent air release valve goes into action and air builds up again on 55 top of equalizing piston in engineer's automatic brake valve; after exhaust of brake pipe air and drop of pressure in brake pipe air equalizes on both sides of equalizing piston and said piston again closes exhaust valve 60 458. The release of air from the equalizing reservoir causes a sudden drop in pressure therein, and the one-inch pipe to hand release 302 is to permit this free flow of air and pressure reduction. Prior to the action of 65 the intermittent release valve the air pres-

sure escapes faster to the one-inch pipe than the air from brake pipe 450 through small passage 464 to feed the chamber over equalizing piston; the pressure from one-inch brake pipe 450 through passage 460 under equalizing piston 457 forces piston up opening its valve 458 to permit air to flow to atmosphere; as air escapes gradually through intermittent release valve 396 to atmosphere from chamber over equalizing piston, it is 70 escaping faster than air from brake pipe can supply through small passage 464 (provided for normally charging equalizing reservoir). Hence, a second lifting of the equalizing piston 457 results with escape of brake pipe air 75 to atmosphere through equalizing piston relief valve.

The piston 457 will graduate off the air pressure and stop operating for from two to three seconds and again come into action 80 completing the twenty pound reduction as popped off or reduced from the equalizing reservoir until equalization takes place between brake pipe and equalizing reservoir, the maintaining air device 224 holding the 85 brakes on the engine and the train, approximating the operation by the engineman in placing the engineer's automatic brake valve on lap position for holding the brakes on the engine and train until it is desired to release the brakes, before or after the train has been brought to a stop. The operation 90 of the automatic brake mechanism will be in force until the train is brought to an automatic graduated service stop, unless the engineman performs the function for manual 95 control by replacing the hand release. Then, after the low speed limit has been reached, controlled by the automatic permissive speed 100 control, the automatic brake mechanism will 105 automatically reset to the normal position and the brakes on the engine and train will go to full release and the train brake system will recharge; the train can proceed under 110 the low speed limit hereinafter more fully 115 described.

The pipe 504 is connected to valve body 223 at 507 to supply air for actuating cylinder 302 on release of valve 239. Device 302, hereinafter referred to as hand release (see 120 Figs. 2 and 3) consists of a cylinder *a*, with cap head *b*, a stop against piston *c*, a check valve *d* with operating lever *e* for releasing air pressure in cylinder *a* for release of same for closing circuit at switch 95, the check 125 valve *d* having a much larger port for exhausting the air than the port *f* shown through rod *g* for air inlet to cylinder. The spring *h* returns cylinder *a* to normal position after release of air pressure for closing circuit at switch 95. This switch is in the circuit of the permissive maintaining circuit of the automatic brake valve and automatic maintaining air valve. While traveling in other than a clear block the switch 95 has a 130

contact plate *l* for completing the circuit from switch fingers. There are two switch fingers, *x*, *y*, located on insulation as shown fastened to base of the device; the contact plate is located on insulation which is attached to and moves with the cylinder. The pipe 504 supplies air pressure for moving the cylinder following release of valve 239.

10 *Traveling maintaining air supply pipe cut out device.*

As exemplified in my aforesaid copending application, means are provided in the brake mechanism to interrupt the feed pipe supply 15 to the train brake pipe and equalizing reservoir. The present invention provides means to automatically cut off the supply of the maintaining air during automatic application of the brake mechanism so as not 20 to interfere with the proper holding action of the same. The automatic cut off in the supply pipe of the air brake mechanism acts to hold the brakes on the train and vehicle to get the same results that follow the manual 25 operation of lever 440 of the engineer's automatic brake valve by the engine driver which is moved to lap position to cut off the maintaining air supply passage to the brake pipe and equalizing reservoir in order to 30 hold the brakes on the train or vehicle until a release of the brakes is desired. This movement of the engineer's automatic brake valve to lap position by the engine driver follows a service application of the brakes. 35 The device is a maintaining air device at all times except when coming into action on entrance to an unclear block. This is accomplished in the present exemplification by the maintaining air device 224. When the 40 traveling mechanism departs from the set-up for clear condition, the electric translating device 212 is deenergized and opens switch 208 which controls the circuit of the electric translating device 236, as heretofore explained, and the valve 238 closes. Valve 45 238 is normally open and controls the passage of maintaining air through the sections 411, 412, of a feed pipe (see Figs. 2 and 3), the section 411 receiving the maintaining air 50 from the feed valve of the brake system and section 412 delivering the maintaining air to the train brake pipe at port 439 and to the equalizing reservoir through port 464 in suitable manner, to be hereinafter more fully 55 explained.

The valve 238 is actuated by a piston 414, connected therewith by a rod 415. The piston slides in a cylinder 416. The cylinder has connection with the inlet-valve *i* and the 60 outlet valve *l* of the electro-pneumatic valve 235, by means of a passage 417. The area of piston 414 is greater than the area of valve 238.

In the present exemplification, the operations which take place when the vehicle

is traveling in block B and its traveling contact coacts with the local contact in said block, take place when the vehicle is traveling in block C and its traveling contact coacts with the local contact of said block, 70 compelling the engineer or driver to manually assume control of the traveling mechanism, failing which the train or vehicle will automatically come to a quick service brake stop in advance of its entrance into a danger block D. 75

Automatic speed limit control.

An automatic low speed limit control device for maintaining the automatic brake control devices in set up position under a fixed low speed limit, for permissive proceed with vehicle traveling in other than a clear block is provided.

The speed control device is exemplified as 85 consisting of the following instrumentalities (see Figs. 6, 7, 8, 9, 10, 11).

Thus, electro-magnet 40 is of the well known iron clad type with outer casing 40a forming one pole of the magnetic field. 45 is a soft iron core forming the other pole of the magnetic field. 41 is an armature, this armature being for instance a soft iron disk. The armature is provided with a stem 44 of a non-magnetic metal, the stem passing through the soft iron core 45 for actuating the electric circuit interrupter, switches 42, 43. The magnet 40 is provided with two windings, 53, 54. Winding 54 is energized from source of electric energy from a traveling generator 65 as will be hereinafter described. The winding 53 is energized from a source of electric energy from the traveling battery 121.

The object of the speed control is to provide an automatic control means for automatically giving service application of the brakes on the traveling vehicle when traveling in other than a clear block should the vehicle exceed the speed of a set up or predetermined low speed limit. The windings 53, 54, forming the two separate magnetic fields have the same magnetic value but are so connected with the source of electric energy as to create opposing magnetic fields; therefore there are two separate wound field coils of opposite polarity with opposing magnetic fields; then, if the electric energy delivered to each field winding is of the same relative value the magnetic field will be neutral, that is, the magnetic flux is *nil*, with no action on the armature 41, and the switches 42 and 43 remain in open position and will remain open until the electric energy supplied to one of the field windings is either decreased or increased in value, accomplished by decrease or increase in electrical energy value or by the insertion in the electric circuit of one of the windings, a resistance 61 shown as a German silver or chrome wire with taps for ad-

justment purposes; the resistance inserted is for the purpose of adjusting the electric value in the winding 53 for the purpose of obtaining any desired pickup point of the 5 magnet to control the releasing point of the brakes for any desired speed of the train.

It is proposed to insert the adjustable resistance in winding 53 which is the winding supplied with electric energy from the source 10 of electric energy supplied from the traveling battery 121, shown as a storage battery of the Edison type or of the well-known lead plate type. Thus the electrical energy supplied to the winding 53 has a constant value.

15 The winding 54 of opposing polarity and supplied with a source of electric energy from a generator of special construction which is driven from the axle of the vehicle, the generator providing novel means in construction, having the characteristics for supplying a positive indicated electrical energy, volts-amperes rating at indicated speeds, and will be referred to hereafter as a tachometer generator.

20 There are two field windings 53 and 54, energized by two separate sources of electric energy. Winding 53 supplied with a source of electric energy of constant value, from a source of electric energy supplied from battery 121, and a winding 54 of opposing polarity inducing a magnetic flux in the polar pieces 45 and 40a opposing the magnetic field of the winding 53. The electric energy supplied from the tachometer generator will 25 increase in value proportionately with the increase in speed of the generator. Then, if the windings 53 is in closed circuit relation with the traveling battery thus inducing a magnetic flux in polar pieces 40A and 45, 30 the armature 41 will pick up completing the magnetic field, and will remain energized as long as the circuit of the winding and battery is in closed position.

35 The armature will remain unattracted as long as the generator is supplying electric energy of such value to the windings 54 as to neutralize the magnetic flux of opposing winding 53 in circuit with the traveling battery. The electric energy supplied by the 40 generator increases with the speed of the generator the construction being such that the electric energy output is graduated up to a given speed as one thousand revolutions per minute, and reaching the maximum electrical value (volts amperes) at this speed. The value will not increase for any increase 45 of speed of the generator above this speed.

An adjustable resistance is provided in the circuit of the traveling battery and winding 53 of the speed control magnet for controlling the speed of the vehicle at any pre-determined speed.

50 The electro-magnet 40 and speed control device above described, operates the brake mechanisms and visible signals on the travel-

ing vehicle when the vehicle is traveling in other than a clear block, and does not function during travel of the vehicle in a clear block, and goes into action for maintaining the automatic electro-pneumatic devices of 55 the brake mechanism shown as the automatic service brake valve 223 and the automatic air maintaining valve 224 in set up position, with the vehicle traveling below the speed limit, adjustment through control circuits by 60 electric conductor 122 from positive pole or traveling battery 121, an electric conductor 140, electric conductor 141, electric conductor 59, switch 127, electric conductor 60, electric conductor 93, switch 43, electric conductor 94, switch 95, electric conductor 96, electric conductor 97, through winding of electric translating device 233, electric conductor 98 to negative terminal of the traveling battery and electric conductor 96, electric conductors 211 and 210, through winding of electric translator device 236, electric conductor 99, electric conductor 133 to common terminal of battery.

55 Provision is also made to provide a no voltage cut-out switch 64 (see Fig. 8) shown as an electromagnet A with winding B and armature C and contact D; the movement of armature C actuates contact D by movement of arm E. The winding is connected as shown (see Fig. 2) across the terminals of the generator; the purpose of the device is to provide means for opening or breaking the circuit of the traveling battery to winding 53 of speed control electromagnet 60 should the tachometer generator fail to deliver electric energy; this is to make a positive open circuit following a failure of the tachometer generator; then, if the tachometer generator fails to deliver electric 65 energy on the entrance to an unclear block the electromagnet 40 of the speed control may be energized and armature 41 holds switches 42 43 in closed position. However, the magnet will be deenergized and will release when the shoe on the vehicle coacts with a ramp rail, caused by the opening of circuit switch 127 under control of the shoe; then the magnet will remain in open position after circuit switch 127 closes as the shoe 70 leaves the ramp rail on account of the maintaining traveling circuit remaining in open position at switch 42 by electric conductors 122, 140, 141, 59, switch 127, electric conductor 60, resistance 61, electric conductors 20, 22, 23, electric conductor 30, switch 42, electric conductor 25, winding 53, electric conductors 28, 29, to common negative battery, and circuit open at armature 21 of no voltage switch 64; a service application of 75 the brakes will follow as usual and the engineman will not be aware of the fact of failure of speed control to function until vehicle brakes have failed to release as is usual with the device in proper working 80

order, after train speed is reduced below limit speed set up.

However, the engineman can again place the electromagnet 40 of the speed control in set up condition by operating a pick up circuit through switch 300 and electric circuit 190 from positive pole of battery, resistance 191, switch 300, electric conductor 92, terminal 26 of the coil 53 and terminal 27, electric conductor 28, electric conductor 29 to the negative terminal of the traveling battery, thus energizing the electromagnet 40; the release of the brakes will follow and the train can proceed, but without the speed control feature. The electromagnet 40 will again be deenergized by the opening of the traveling battery circuit at switch 127 operated by the movement of the shoe. When it coacts again with a ramp-rail at the entrance to block in advance the service brake application is again repeated as before explained, if the block in advance is in unclear condition. Now, if the vehicle enters a clear block leaving an unclear block the translating devices 103 and 212 will coact with the shoe devices and the maintaining traveling battery circuit for clear block will again set up in closed circuit relation with the automatic service brake valve and the automatic maintaining air valve, and the visible signal in the cab of the vehicle will change from green and yellow, to green, indicating a clear block and the engineman can proceed at speed. As the speed control devices do not function in a clear block but as before explained, the service application of the brake mechanism will come into action on entering other than a clear block, regardless of the failure of the tachometer generator or either one or both of the field windings on the electromagnet 40 of the speed control device.

Separate manual control of unclear condition of traveling mechanism.

As hereinbefore explained, the traveling signaling and vehicle control mechanism is placed in unclear and brake applying position when the traveling contact coacts with the local contact located in rear of a caution block or a danger block, with the result that the train or vehicle will be stopped as hereinbefore explained, unless manual control of the same is assumed by the driver or engineman. If the engineman is incapable of such manual control for any reason, whether he be away from his post, or sick, or dead, the vehicle or train will stop. It may be timed so that the stoppage will occur before the train or vehicle reaches the danger block. Under the traffic rules the engineer may travel in a caution block with his train under control, and may proceed into an automatic block indicating stop only after bringing the train or vehicle to a full stop

then proceeding at low speed, say from three to five miles per hour, expecting to find a train in the block, an open switch, or train fouling, or a broken rail, requiring the engineman to have his train under full control to expect a danger condition ahead. This is in accordance with the established automatic signal rules for train movements.

There is furthermore, a signal for indicating to the engineman that he is traveling under a permissive control, and in an unclear block or section of track. The signal in this instance is a combined green light and yellow light, indicating a permissive proceed or travel in an approach to or within an unclear block.

The green light is in a circuit comprising the common positive electric conductor 96, tapping switch 95 of the hand release, electric conductors 211, 209, 213 to green bulb 85 A and electric conductors 214, 205, 131, 132, and 133 to the common negative pole of the traveling battery.

The yellow light signal indicating an entrance to an unclear block will continue to indicate in the electric circuit comprising the common positive traveling battery 122, 140, 141, 207, back contact of switch 208, the electric conductor 213A, to the electric bulb B of the yellow indication, and to the common negative pole of the traveling battery by electric conductors 214, 205, 131, 132 and 133. When the traveling system is proceeding in unclear block under control, and under the speed limit control and approaching an unclear block either a caution block or a red block, the engineer must operate and hold a switch 300 in closed relation during the time of coaction between the traveling shoe contact 101 and the local contact 90 to prevent an automatic service brake application which would follow should engineer not operate the manual control switch 300 which closes a circuit to control the automatic service brake 110 valve 223, and the maintaining air valve 224, to place these valves out of the influence of the unclear condition of the mechanism, the circuit for this manual control comprising an electric conductor 190 from the positive 115 pole of the traveling battery through a resistance 191, a switch 300, electric conductor 92, to terminal 26 of the translating device 40 of speed control through winding 53, to terminal 27 and electric conductors 28 and 29 to the common negative pole of the traveling battery. This manual control for permissive entrance into an unclear block is necessary for safety as the engineman may be absent from his post at the moment of such entrance or the passage over the local contact or may be incapacitated and not notice the audible signal.

The manual control does not influence the electric translating devices 103 and 212 there- 130

fore these devices remain in deenergized relation during travel in other than a clear block, but will come into action at the first coaction of the traveling contact shoe and 5 local contact at entrance to a clear block, thereby setting up the electric translating devices 103 and 212 in closed condition, again closing the high speed control circuits for maintaining the automatic service brake 10 device 223 and maintaining air device 224 in set-up or closed condition; also the green electric light signal will indicate while the yellow signal light will disappear. During 15 the travel of the train and vehicle in an unclear block the train must necessarily remain under the permissive speed limit control; to increase the speed above the set up speed of the control device will cause automatic application of the brake mechanism 20 caused by the tachometer generator increasing speed to a point where the electric energy supplied to winding 54 of the electrical translating device 40 neutralizes the magnetic flux in the field pieces under influence 25 of winding 53 and the traveling battery and thereby causes the armature 41 to release and the opening of switches 42 and 43 and the breaking of the permissive control circuit of the automatic brake mechanism. 30 However, the application of the brakes will be very light as the train speed would be immediately reduced below the set speed limit and the automatic service brake mechanism will return to normal and stop further 35 brake pipe reductions. However, the hand release must be replaced by the engineman immediately to close the maintaining permissive control circuit at switch 95, to obtain the stoppage of brake reduction after train 40 is under the limited speed and thereby complete the control circuit to the automatic brake mechanism. Immediate action on the part of the engineman will prevent a full service brake pipe reduction as a very small 45 reduction would bring the speed of vehicle below the limited speed set up.

During such functioning of the traveling mechanism the engineer may operate the engineer's automatic brake valve in the usual 50 manner for stopping train or reducing the speed of train. During the time of automatic brake action, or immediately following the same, the engineman can by operating the automatic brake valve make a 55 heavier brake pipe reduction should it be necessary to make a quicker stop or to make an emergency application of the brakes, as the automatic brake mechanism does not interfere in any way with the usual operation 60 by the engineer of the engineer's automatic brake valve. Of course, it is understood that the engineer would make a lighter reduction than usual for a service stop following an automatic action of the brakes, according to the weight and speed of the train 65

and the stopping distance. A brake pipe reduction is governed and indicated by the usual air gages in the braking system.

Control circuits of the speed control devices. 70

I have exemplified such means as comprising speed control means for retarding the release of brakes caused by the coaction of a traveling tachometer generator and an electric translating device, and shown as means 75 for retarding the closing or pick up relation of the maintaining circuit of the traveling battery following an interruption of the maintaining circuit influence of the automatic brake mechanism caused by the 80 coaction of the traveling contact with the local contact. When the block in advance is other than a clear block, and the train speed is greater than the low speed limit adjustment of the vehicle, means is provided for 85 holding the brakes on the vehicle and train until the speed has been reduced below the permissive speed limit control.

The speed control means is shown as connected with the traveling automatic signal mechanism. These means are exemplified as consisting of the following instrumentalities, hereinbefore described: an iron clad electromagnet 40 with armature 41 for actuating switches 42 and 43 by armature stem 95 44 passing through iron field core 45, and striking lever 46. The switches are hinged at 47 and are held in open position by a spring 48, a terminal 49 for one side of the circuit is a part of the switch finger 42; the other terminal 50 has a contact point for completing the circuit when the switch is closed. The actuating lever 46 is insulated from the switch finger by suitable insulation at 51a, a non-magnetic cap 52 is held in place over the end of the magnet 40 on the outer casing for the armature housing, the armature 41 is adjustable by lock nuts on the non-magnetic stem 44. 100

The signal system, as shown in the drawing (Fig. 2) is set up for clear condition 110 and with the train or vehicle proceeding at high speed. The electric energy supplied by the tachometer generator holds the speed control magnet device in open condition; however, the automatic signaling system must necessarily be placed in the high speed condition only after coaction of the traveling shoe and the local ramp-rail at the entrance to the first clear block after leaving 115 the engine terminal as the automatic signaling mechanism cannot be placed into clear condition by manual operation.

Assuming that the engine is being prepared for road service in the engine house 125 or terminal and reaching the time when the air brake system is ready for the usual testing; then, before the air brake system on the engine can be built up by the air pump the electric circuit of the automatic signal 130

must be placed in closed or energized condition, as the brake pipe is open to atmosphere through the automatic service brake valve 223, and the automatic maintaining air valve 224 is closed, shutting off the air supply in the feed pipe between the main reservoir and the braking system; therefore the braking system of the vehicle is not available until the automatic signaling system has been placed under the influence of the traveling battery.

The method of proceeding to place automatic signaling mechanism in closed condition is as follows: First, the main traveling battery circuit is closed through main battery switch; this must be followed by manual operation of the permissive switch 300 hereinbefore described thereby energizing speed control electromagnet 40 and attracting the armature and actuating switches 42 and 43 to closed positions and closing a maintaining circuit for the magnet 40 comprising the common positive pole of the traveling battery, electric conductors 122, 140, 141 and 59, the switch 127, an electric conductor 60 to terminal of resistance 61, the resistance to terminal 62, electric conductors 20 and 30, the terminal 50, the switch 42, the contact and terminal 49, an electric conductor 25, terminal 26, through winding 53 the terminal 27, electric conductor 28, the conductor 29 to the common negative pole of the traveling battery. The automatic brake mechanism will be placed in closed position by energizing electric translating devices 236 and 233 by a maintaining electric circuit comprising the common positive electric conductors 122, 140, 141 and 59, the switch 127 an electric conductor 60, electric conductor 93, the switch 43, electric conductor 94, hand release switch 95, an electric conductor 96, electric conductor 97, to the terminal and through translating device 233 of the automatic service brake valve, and electric conductor 98 to the common negative pole of the traveling battery, electric conductors 211 and 210, through translating device 236 of the automatic maintaining air valve, electric conductors 99 and 133 and the negative pole of the traveling battery, an electric conductor 211, electric conductors 209 and 213 to green signal electric light bulb "A," electric conductors 214, 205, 131, 132 and 133 to common negative pole of the traveling battery, the yellow signal light indicating through an electric circuit conductor 122 from positive traveling battery, electric conductors 140 and 141, back contact switch 208 and electric conductor 213A through electric bulb "B" and electric conductors 214, 205, 131, 132 and 133 to the negative pole of the traveling battery. Thus, the green and yellow signal light indicate that the automatic signaling system is

in the permissive proceed control; the air brake system can then be tested. The signal system will remain in this control position and compel the engineman to proceed under low speed limit as regulated until coaction of traveling shoe and local ramp-rail at the entrance to the first clear block.

Loss of traveling contact.

Means are further provided whereby, when the traveling contact or shoe 101 is broken away or lost, the stem 154 will drop opening maintaining battery circuit for translating device 212 by opening of switch 128 thereby applying the brakes, but the driver may continue travel under the permissive signal indicated by signal lights yellow and green.

THE BRAKE SYSTEM.

Automatic and manual application of brakes.

Any part of the invention having connection with a brake system may be used in connection with any brake system desired. The invention is exemplified as used in connection with the Westinghouse ET locomotive brake equipment, shown and described, for instance, in the publication entitled "The Westinghouse No. 6 E-T Air Brake Instruction Book" by W. W. Wood, published by the Norman W. Henley Publishing Company of New York city, N. Y., and the "No. 6 E-T Locomotive Brake Equipment" published by the Westinghouse Air Brake Company, Pittsburgh, Pa., reference being made to these publications and to other publications and to the art for a more complete exposition of these systems, if the same be desired, only so much of the systems being shown herein and described as it is believed necessary for an understanding of the present invention. Portions of the usual air brake system have been heretofore described.

The pressure from the main reservoir 241 leads through pipes 242, 435 to a feed valve 436. The construction and function of the feed valve is well understood in the art. The feed valve is exemplified as a double pressure feed valve, which has an operating handle 437 in order to regulate the pressure of the air which passes from the main reservoir into the pipe 411 and thence through the maintaining air device 224, pipe 412, a valve 439 in the engineer's automatic brake valve, and a pipe 450 into the train brake pipe 398 and passage 464 to chamber 455 and to equalizing reservoir 453. (See Figs. 2 and 3.)

When the handle 437 is set in one position, the valve is arranged to supply a less pressure for instance seventy pounds per square inch, to the train brake pipe and equalizing reservoir, the handle can be adjusted to a higher pressure for instance

ninety pounds or 110 pounds per square inch supply to the train brake pipe and equalizing reservoir.

The valve 439 is closed when the engineer's automatic brake handle 440 is in lap position for holding the brakes on the engine and train, and in the holding position for holding the brakes on the engine and tender and releasing the train brakes and recharging the brake system on the train; when the handle 440 is in the running position, as exemplified in Figs. 2 and 3 of the drawings, the valve 439 is open, and the supply pressure from the pipe 412 passes through into the pipe 450 and thence into the train brake pipe 398 and maintains or builds up loss of pressure there may be therein due to ordinary leakage in the brake pipe and its connections or following an application of the brakes. When the handle 440 is moved to the service position to make a service application of the brakes, the port in valve 439 is closed to shut off the supply of air from feed pipe 412 to make the brake pipe reduction effective for applying the brakes; then to hold the brakes following the brake pipe reduction with handle 440 in the lap position, the handle 440 is quickly moved to lap position which position also blanks the feed pipe at valve 439 to prevent again building up the brake pipe which would automatically release the brakes.

In the present exemplification of the invention, the automatic actuated valve 238 of the maintaining air device 224 serves a similar purpose automatically when the vehicle signal control system is conditioned for an automatic service application of the brakes and holding the supply or feed pipe 412 in closed position until the automatic release of the brakes made after the engineer manually operates the hand release after the train or vehicle has traveled into an unclear block, the valve 238 thereby automatically preventing the building up of pressure in the brake pipe or its connections which would affect the applying of brakes or the applied condition of same, thereby obtaining the same effect as that which the lever 440 placed in the lap position for holding the brakes on locomotive and train. There is, however, nothing to prevent engineer operating lever 440 of the engineer's automatic brake valve and making a further reduction of the brake pipe air pressure at any time during the automatic brake pipe reduction or following the same should it be necessary to make a shorter stop of the train such as an approach to and a stop at a station; but the engineer cannot release the brakes of the train during automatic application, as the valve 396 will continue to make the reduction from the equalizing reservoir 453 through pipe 395 and valve

223 until the adjusted brake pipe reduction of for instance twenty pounds has been made, and the engineer cannot in any way during high speed travel of the train, release the automatic brake mechanism until the speed limit control has actuated, it being understood that release of the brakes is accomplished by the building up of the pressure in the train brake pipe, that is, by a quick recharging of the brake pipe with the excess pressure obtained direct from the main reservoir, which pressure is maintained at twenty pounds in excess of the brake pipe pressure. This pressure is admitted through a port of the engineer's automatic brake valve when the lever 440 is in full release position in which position the lever is held for an instant only to quickly recharge the brake system and insure the release of the brakes on the train and equalize the pressure in the brake pipe and equalizing reservoir.

The valve 239 of the service brake application device 223 has connection with the usual equalizing reservoir 453 by a pipe 395 and pipe 454 (see Fig. 2) the pipe also connecting with the equalizing chamber 455 in the engineer's automatic brake valve by means of a passage 456, the equalizing reservoir being for the purpose of increasing the cubic contents of the said equalizing chamber, the air in the equalizing reservoir acting as a reserve force to actuate the piston 457 intended to be actuated following gradual reduction of pressure in the equalizing reservoir, allowing the brake pipe pressure under the equalizing piston to raise it and unseat its valve 458, allowing brake pipe air to flow to the atmosphere gradually through the exhaust port 459 by repeated operations of the equalizing piston. The gradual reduction of the brake pipe pressure is to prevent quick action and the gradual stopping of the discharge or exhaust is to prevent the pressure at the head end of the brake pipe being built up by the air flowing from the rear, which might cause some of the head brakes to kick off.

Air will continue to discharge from the brake pipe until its pressure has fallen to an amount a trifle less than that retained in the equalizing reservoir, permitting the pressure in the chamber over graduating piston to force the piston downward gradually and stop the discharge of brake pipe air. The equalizing piston is so arranged when the handle 440 is in the running position, that there is equal pressure at both sides thereof. The equalizing pressure above the piston 457 is supplied from the feed pipe 412 through a port 464 in the rotary valve 463 of the engineer's automatic brake valve. The pressure below said piston is received from pipe 450 through the port 460.

When the electric translating device 233 of the automatic service brake application device 223 is deenergized for closing the inlet valve *i* thereof, the valve 239, which is normally closed, is thereby opened, for admitting the air to the intermittent air release valve 396, as hereinbefore explained, whereby pressure is relieved in the equalizing reservoir and in the chamber 455 above the equalizing piston, for moving the latter and opening the valve 458 (see Fig. 3). The automatic opening of the valve 458 causes relief of pressure in the train brake pipe through the passage 460 and pipe 450 for causing application of the brakes, such as a service application, the extent of this application being dependent on the extent of the relief of pressure from the equalizing reservoir consequent upon the adjustment of the valve 396 and may be ten, fifteen, twenty or twenty-five pounds. When the pressure in the train brake pipe has been relieved through the valve 458 to cause this pressure to be substantially equal to the pressure in the equalizing chamber above the piston 457, the valve 458 is automatically closed. The brakes will continue to hold until the vehicle or train is brought to a stop or until the speed control devices actuate at the speed limit adjustment, and the engineer has assumed control of the signal system in a manner hereinbefore described.

The automatic stoppage of the train is gradual and without jar, and the stopping distance according to the brake pipe reduction, and the weight and speed of the train. Practice has demonstrated the inadvisability of an emergency stop for the vehicle or train, as the damage resulting is sometimes equal to that of a wreck and in any event is injurious to the rolling stock. An automatic service application of the brakes fills the requirements for safety as the train can be brought to a stop or under control after coaction of the traveling contact and the local contact which local contact ramp rail is located in advance of the entrance to the block a sufficient distance to protect traffic according to the traffic and speed regulations, alignment and gradients that will vary.

In order to place the automatic brake application mechanism completely under control of the automatic brake control, and prevent the pressure in the train brake pipe and equalizing chamber and reservoir from again being built up by the feeding of pressure from the feed valve 436, the electric translating device 236 of the maintaining air device 224 has also been deenergized for closing the valve 238 thereby automatically shutting off the pressure feed from the feed valve to the train brake and equalizing reservoir. This automatic shutting off of

pressure is continuous throughout the time 65 that automatic brake application and until manual control is had, and in case of high speed over and above the speed limit, until the train or vehicle is under the speed limit control, when the brakes will automatically 70 release and will recharge the brake system and equalization will take place in the brake pipe and equalizing reservoirs.

Local contact ramp-rail protection.

The local contact or ramp-rail is a section of T rail bent at each end to effect a gradual shoe contact and avoid shock to shoe and mechanism. The ramp rail is supported on insulated brackets on the extension of the traffic rail ties, the local track battery 61 for block B, under control of the signal controlling the entrance to block C, has the electric conductors 72 and 73 from battery 61 to track circuit B attached to the ramp rail through a porcelain attachment but not in electric contact with the ramp rail; this arrangement is to break the local track battery circuit in the block in the rear instance as block B for breaking the local battery circuit to ramp rail indicating the condition of block B, that advance information of the absence of the ramp rail should same be destroyed or removed by an unclear set up made on the traveling 95 vehicle or train. (See Fig. 1).

The breaking of the track battery electric conductors 72 and 73 to traffic rail 11 and 12 under control of block "C" will deenergize the track relay 74 controlling block B thereby opening armature 48 and positive battery electric conductor 89 of the local battery to ramp rail 90, therefore indicating an unclear condition of the traveling vehicle on coaction of traveling shoe and local contact 90. Then too, the signal rules will include for permissive running, proceed expecting to find a train in the block, an open switch, a broken rail, train or cars fouling on siding, or ramp rail deranged or missing.

The tachometer generator.

The tachometer generator 65 is exemplified as comprising a permanent built up steel magnetic field 520 (see Figs. 10 and 11). There being no electromagnetic field, the magnetic field is produced entirely by permanent magnets on the machine. This generator will produce a voltage absolutely proportional to the speed at which it is run.

The permanent steel field 520 has an insulating casing 552 of paper fiber $\frac{1}{8}$ " in thickness and an aluminum casing, 553 covering the fiber casing for the purpose of protecting the permanent steel field from influence of any iron or steel parts of the locomotive on which the generator is located; further to protect the polar pieces

554 and prevent any foreign influence of the field or polar pieces, and also to prevent the magnetic field from short-circuiting to any metal part of the engine or support across 5 the pole pieces. The two plates 555 and 556 are $\frac{1}{2}$ " aluminum metal with a brass plate 557 as a separator; the holding bolts 558 are brass; the generator pulley is built up 10 fiber with deep groove to accommodate the $\frac{1}{2}$ " spiral steel driving belt; the driving pulley on the locomotive is located on outside and bolted to the end of the pony truck axle. The terminals 51 and 57 of the generator are located in an aluminum housing 559.

15 For any change in the release of the magnetic armature 41 of the electromagnet 40 the adjustable resistance 61 is provided in circuit of the winding 53 to regulate the release and pick up point of the magnet armature. A spring 48 also assists in the release 20 of the armature when the electric energy value of the tachometer generator has reached a value to weaken the magnetic field of the electromagnet 40 to a degree that the 25 armature releases and remains in this released or open relation as long as the vehicle or train is running above the adjusted pick-up point of winding 53.

It is obvious that changes in construction 30 and arrangement of the parts and circuits may be made without departing from the spirit of the invention within the scope of the appended claims.

Having thus fully described my invention, 35 what I claim as new and desire to secure by Letters Patent is:

1. In combination, with brake mechanism, of traveling mechanism including means for clear condition of block ahead and means 40 for unclear condition of block ahead, said means for unclear block ahead including means for automatic graduated service application of the brakes, and means for interruption of maintaining-air in the brake 45 mechanism.

2. In combination with brake mechanism, of traveling mechanism including means for clear condition of block ahead and means for unclear condition of block ahead, said means 50 for unclear condition of block ahead including means for automatic graduated service application of the brakes and automatic graduated release of the brakes and automatic speed control means controlling the 55 automatic graduated application of the brakes and automatic graduated release of the brakes.

3. In combination with brake mechanism, of traveling mechanism including means for 60 clear condition of block ahead and means for unclear condition of block ahead, said means for unclear condition block ahead including means for automatic graduated service application of the brakes, and automatic 65 means for interruption of the maintaining-

air brake mechanism and automatic low speed control of automatic brake mechanism.

4. In combination, with brake mechanism, of traveling mechanism including means for clear condition of block ahead, and means for unclear condition of block ahead including means for automatic graduated service application of the brakes and means for automatic interruption of the maintaining-air 70 in the brake feed pipe of the mechanism and automatic speed control means for interrupting the automatic graduated release of the brakes and interrupt the release of the maintaining-air means. 80

5. In combination, with brake mechanism of traveling mechanism including means for clear condition of block ahead, and means for unclear condition of block ahead including means for automatic graduated service application of the brakes, and means for the automatic interruption of the maintaining-air in the feed pipe in the brake mechanism, and automatic speed control mechanism for retarding the automatic 85 graduated release of the brake mechanism and the release of the brakes when vehicle or train is traveling at a speed above the adjusted low speed limit control on entrance into an unclear block. 95

6. In combination with brake mechanism of traveling mechanism, including means for clear condition of block ahead and means for unclear condition of block ahead including means for automatic graduated service application of the brakes, and means for automatic interruption of the maintaining-air in the feed supply pipe in the brake mechanism and automatic speed control means for limiting the traveling speed of 100 vehicle or train in an unclear block, and manual means for interruption of said service brake application means and said maintaining-air means for traveling under limited speed control and entrance into an unclear block. 105

7. In a system of the character described, the combination with a track divided into blocks, a traveling contact shoe making contact with ramp rails in said block, a control device coacting with the current received through said contact shoe for maintaining the air brake system in normal relation, said control device consisting of two automatic air valves controlled by electro-pneumatic valves, said valves also controlling intermittent air release valve for producing a graduated application of the brakes upon entrance of the vehicle into a block other than a clear block. 115

8. In a traveling system, the combination of local energizing partial circuits, local control means for said respective local partial circuits, a traveling partial circuit including a source of electric energy, traveling con- 120

130

- trolled devices arranged to be set up in accord with the said local partial circuits, said traveling partial circuits arranged for continuance of said set up relation, a traveling 5 air discharge valve and a traveling maintaining-air device for an air-brake system, and circuit connections including said source of electric energy for controlling said air discharge valve and said maintaining-air 10 valve, said circuit connections controlled by said traveling controlling devices.
9. In a signal system for railways the combination of local energizing partial circuits, local control means for said respective 15 local partial circuits, a traveling partial circuit, a traveling partial circuit including a source of electric energy, traveling controlled devices arranged to be set up in accord with the local partial circuits, said 20 traveling circuits arranged for continuance of said set-up relation, a traveling air-brake discharge valve for an air brake system, an electric translating device therefor, a control device for the latter, including an electric 25 translating device, circuit connections including said source of electric energy for controlling said electric translating devices, and means for controlling electric flow through said translating devices.
- 30 10. In a system of the character described the combination of local energizing partial circuits, local means for controlling said local partial circuits, a traveling partial circuit including a source of electric energy, traveling controlled devices arranged to be set up in accord with the respective local 35 partial circuit arranged for continuance of said set-up relation, a traveling graduating service application device for service application 40 of an air-brake system, a maintaining-air device for shutting off the maintaining-air supply of the air-brake system, and electro-pneumatic valves controlling the last two named devices, an electric translating 45 device for maintaining said electro-pneumatic valves.
11. In a system of the character described, the combination of a local partial circuit including a local source of electric energy, a 50 circuit interrupting means, a traveling partial circuit including a pick up electric translating means from local source of electric energy, a traveling circuit for holding said pick up translating device in closed position, and retarding means by a dash pot control for timing the return to normal open 55 position of said traveling electric circuit and pick up translating device.
12. In a system of the character described, 60 the combination of an energizing local partial circuit including local electric transferring means, a traveling partial circuit including a traveling source of electric energy, a vehicle braking means, a vehicle speed limit control means, a traveling partial
- 70 maintaining circuit for maintaining the brakes in released relation, a traveling partial circuit including an electric translating device, a traveling electric transferring means therefor, and means actuated by coaction of the latter with said local electric transferring means for placing said traveling partial circuit including said electric translating device into coaction with said traveling partial circuit including said traveling 75 source of electric energy for placing said traveling partial maintaining circuit under influence of said energizing local partial circuit.
13. In a system of the character described, 80 the combination, with air brake mechanism of automatic control means for automatic graduated air reduction from the equalizing reservoir of the air brake system to cause the equalizing piston in the engineer's automatic 85 brake valve to raise and unseat its valve allowing brake pipe air to flow to the atmosphere gradually to cause a service application of the brakes on locomotive and train.
14. In a system of the character described 90 the combination with air brake mechanism of automatic control means for automatic graduated air reduction from the equalizing reservoir of the air brake system to cause the equalizing piston in the engineer's automatic 95 brake valve to raise and unseat its valve allowing brake pipe air to flow to the atmosphere gradually to cause a service application of the brakes on locomotive and train, and automatic speed control means affecting 100 the operation of said automatic brake control means.
15. In a system of the character described the combination with air brake mechanism of automatic control means for automatic 105 graduated air reduction from the equalizing reservoir of the air brake system to cause the equalizing piston in the engineer's automatic brake valve to raise and unseat its valve allowing brake pipe air to flow to the atmosphere gradually to cause a service application of the brakes on locomotive and train, and automatic speed control means affecting 110 the operation of said automatic brake control means, and manual control means.
16. In a system of the character described the combination with air brake mechanism, of automatic control means for automatic 120 graduated air reduction from the equalizing reservoir of the air brake system to cause the equalizing piston in the engineer's automatic brake valve to raise and unseat its valve allowing brake pipe air to flow to the atmosphere gradually to cause a service application of the brakes on locomotive and train, and means for adjusting the duration of reduction from the equalizing reservoir.
17. In a system just described, the com- 130

bination with air brake mechanism of automatic control means for automatic graduated air reduction from the equalizing reservoir of the air brake system to cause the 5 equalizing piston in the engineer's automatic brake valve to raise and unseat its valve allowing brake pipe air to flow to the atmosphere gradually to cause a service application of the brakes on locomotive and train, 10 and manual means for interrupting said automatic air reduction from equalizing reservoir.

18. In a system just described, the combination with air brake mechanism, of automatic control means for automatic graduated reduction from the equalizing reservoir of the air brake system to cause the equalizing piston in the engineer's automatic brake valve to raise and unseat its valve, allowing 20 brake pipe air to flow to the atmosphere gradually to cause a service application of the brakes on locomotive and train and automatic low speed limit control means for automatically holding the brakes applied on 25 the locomotive and train after automatic service until train speed is reduced to the adjusted low speed limit and automatic means for again applying a service application 30 of the brakes should train exceed the low speed limit.

19. In a system just described the combination with air brake mechanism of automatic control means for automatic graduated reduction from the equalizing reservoir 35 of the air brake system to cause the equalizing piston in the engineer's automatic brake valve to raise and unseat its valve allowing brake pipe air to flow to the atmosphere gradually to cause a service application 40 of the brakes on locomotive and train, and automatic low speed limit control means for automatically holding the brakes applied on the locomotive and train after automatic service until train speed is reduced to the 45 low speed limit, and automatic control means for full release of the brakes on locomotive and train and automatic recharge of the air brake system, and automatic means for again making a service application 50 of the brakes if train exceeds the low speed limit.

20. In a system just described the combination with air brake mechanism, of automatic control means for automatic graduated reduction from the equalizing reservoir 55 of the air brake system to cause the equalizing piston in the engineer's automatic brake valve to raise and unseat its valve allowing brake pipe air to flow to the atmosphere gradually to cause a service application of the 60 brakes on locomotive and train and automatic low speed limit control means for automatically holding the brakes applied on the locomotive and train after automatic service, until train speed is reduced to the low speed 65 limit.

limit and manual control means affecting the operation for full release of the brakes on locomotive and train and automatic recharge of the air brake system.

21. In a system just described the combination with air brake mechanism, of automatic control means for automatic graduated reduction from the equalizing reservoir of the air brake system to cause the equalizing piston in the engineer's automatic brake valve 70 to raise and unseat its valve allowing brake pipe air to flow to the atmosphere gradually to cause a service application of the brakes on locomotive and train and automatic low speed limit control means for automatically holding the brakes applied on the locomotive and train after automatic service, until train has been brought to a stop.

22. In a system just described the combination with air brake mechanism, of automatic control means for automatic graduated reduction from the equalizing reservoir of the air brake system to cause the equalizing piston in the engineer's automatic brake valve to raise and unseat its valve 80 allowing brake pipe air to flow to the atmosphere gradually to cause a service application of the brakes on locomotives and train and automatic low speed limit control means for automatically holding the 85 brakes applied on the locomotive and train after automatic service, until train has been brought to a stop and manual control means affecting the operation of said automatic control means for full automatic release of 90 the brakes on locomotive and train.

23. In a system just described the combination with air brake mechanism, of automatic control means for automatic graduated reduction from the equalizing reservoir of the air brake system to cause the equalizing piston in the engineer's automatic brake valve to raise and unseat its valve 105 allowing brake pipe air to flow to the atmosphere gradually to cause a service application of the brakes on locomotive and train and automatic low speed limit control means for automatically holding the brakes applied on the locomotive and train after automatic service, until train has been brought to a 110 stop and automatic full release.

24. In a system of the character described, the combination with air brake mechanism, of automatic means for interrupting supply of maintaining air in feed valve pipe of 120 said air brake mechanism, and manually operated means for controlling said interruption.

25. In a system of the character described the combination, with air brake mechanism, 125 of automatic control means for automatic graduated discharge of air from the equalizing reservoir of the air brake system for service application of the brakes, and automatic means for shutting off the supply of 130

maintaining air in feed valve pipe in the said air brake mechanism, for holding the brakes applied after automatic service application.

5 26. In a system of the character described the combination, with air brake mechanism, of automatic control means for automatic graduated discharge of air from the equalizing reservoir of the air brake system for 10 service application of the brakes, and automatic means for shutting off the supply of maintaining air in feed valve pipe in the said air brake mechanism, for holding the brakes applied after automatic service application, and manual operated means for interrupting said automatic control means for automatic service application of the brakes, and said automatic means for shutting off the supply of maintaining air in 20 feed pipe.

27. In a system of the character described, the combination with air brake mechanism of automatic control means for automatic graduated discharge of air from the equalizing reservoir of the air brake mechanism for raising the equalizing piston of the engineer's automatic brake valve to raise and unseat its valve allowing brake pipe air to flow to the atmosphere gradually to cause a 30 service application of the brakes, automatic means for interrupting the supply of maintaining air by shutting off said supply in feed pipe of said air brake mechanism, manual operated means interrupting said automatic discharge of air from the equalizing reservoir and manually controlled means for combinedly interrupting said discharge and controlling said last-named automatic means.

40 28. In a system of the character described the combination of automatic control means for controlling service application of the brakes, said service control device comprising an electric translating maintaining device, an electro-pneumatic valve, an intermittent air release valve, an electro-pneumatic valve, a cut off valve in feed pipe of the maintaining air, an electric speed control device controlling the last two named 45 valves, electro-pneumatic valves in unclear blocks for low speed proceed and permissive proceed, and a manually operated switch in multiple with said last-named device.

29. In a system of the character described, 55 the combination of a service control device for controlling service application of the brakes, said service control device comprising an electric translating device, an electro-pneumatic valve for operating intermittent air release valve, an electro-pneumatic valve for operating cut off in feed pipe of the maintaining air, an electric translating device for controlling said automatic brake actuating valves in unclear blocks, for permissive proceed, and manually operated 60

switches for controlling said electric translating device.

30. In a system of the character described, the combination of a service control device arranged for automatic service application 70 of the brakes by relief of pressure in an equalizing reservoir and comprising a brake valve, an equalizing chamber, an equalizing discharge piston and exhaust valve therefor, an automatic pressure discharge means acting 75 on said equalizing discharge piston and valve.

31. In a system of the character described, the combination of a service control device arranged for automatic service application 80 of the brakes by gradual release of pressure from an equalizing reservoir comprising an adjustable intermittent air release valve, and a valve with equalizing chamber, an equalizing discharge piston therefor, an automatic pressure discharge means acting on 85 said equalizing discharge piston and valve, an electro pneumatic valve controlling the last named valve.

32. In a system of the character described, 90 the combination of a service control device for automatic service application of the brakes by relief of pressure in an equalizing reservoir, comprising an adjustable intermittent air release valve for graduating off the 95 pressure in the equalizing reservoir with quick pop action and means to cause pressure in equalizing reservoir to fall gradually.

33. In a system of the character described, the combination of a service control device 100 for automatic service application of the brakes by gradual relief of pressure in an equalizing reservoir comprising an intermittent graduated pressure relief valve with electro-pneumatic control valve release; first 105 named valve has adjustable automatic actuated valve mechanism with retarding exhaust chamber, equalizing valve movement, adjustable automatic pressure discharge means acting on equalizing discharge valve, 110 and automatic equalizing pressure stop, with said automatic exhaust pressure stop not under control of electro-pneumatic control valve.

34. In a system of the character described 115 the combination of a service control device arranged for automatic control of a service application of the brakes by relief of pressure in a brake pipe in other than a clear block and permissive low speed control 120 therefor, comprising a tachometer generator of limited and graduated supply of electric energy driven from the axle of the vehicle, an electromagnetic translating device with two independently wound field coils, electric 125 energy supplied from the generator through one of the coils acting in opposition to the other winding, supplied from a constant source of electric energy with said graduated supply of electric energy in closed relation 130

through one coil winding acting to neutralize the magnetic field induced by the fixed and constant supply of electric energy in closed circuit through the other winding with the 5 polarity of the said constant supply of electric energy connected and flowing in the reverse direction through its winding, the control coil adjusted to energize its magnetic field and actuate and hold in closed relation 10 the switch in the circuit of the automatic brake mechanism when vehicle is traveling under the low permissive speed limit.

35. In a system of the character described, the combination of a traveling shoe, a stem 15 actuated thereby, a movable arm actuated by said stem, control switches actuated by movable arm, a retarding means comprising a dash pot retarding to normal relation said stem movable arm and switches, and automatic means for return of said stem, movable arm, and switches to normal relation 20 after actuated by shoe.

36. In a system of the character described, the combination of a traveling shoe, a stem, 25 an arm, control switches, and a dash pot piston actuated thereby, means for returning said mechanism to normal relation, said piston in dash pot provided with a valve arranged for opening of said valve for full 30 upward movement, and said piston provided with a restricted passage during return movement of said piston for retarding said return movement.

37. In a system of the character described, 35 the combination of a traveling shoe, a stem, arm, control switches and a dash pot piston actuated thereby, means for returning said stem, arm, switches and piston to normal position, a piston and cylinder, said cylinder 40 arranged for receiving a liquid, a valve on said piston for free passage of liquid during upward movement of said piston through said liquid and a restricted passage through piston for return of piston through said 45 liquid during actuated relation for retarding said return movement and means for adjusting said passage.

38. In a system of the character described, the combination of local control means 50 traveling controlled means controlled thereby, a traveling control device for clear condition, and a traveling permissive limited speed control device for unclear condition, including an electric translating device for said

traveling control device, for clear condition 55 thereof, a traveling circuit for said traveling control device for indicating condition thereof, an electric change device in each of said traveling circuits, one of said electric change devices controlled for clear condition 60 for said traveling controlled means, and the other of said electric translating device with opposing control circuits under control of the speed of the vehicle, a traveling source of electric energy supply from the traveling 65 battery of said electric translating device while vehicle is traveling under the permissive low speed and a source of electric energy supply from a generator driven from axle 70 of vehicle as opposing the first named control of the translating device.

39. In a system of the character described, the combination of local control means, traveling control means controlled thereby, traveling control device for clear condition, and 75 traveling permissive control device for unclear condition, a traveling maintaining control circuit with electric translating control device, said electric control device energized in closed circuit relation through switch in 80 closed circuit relation controlled by shoe mechanism for clear condition of block, a traveling permissive control circuit controlled by permissive low speed electric translating device with opposing control circuits, one control circuit for high speed travel of vehicle, and one control circuit for 85 low speed control, both circuits having independent source of electric energy supply, a switch in the low speed control circuit for 90 control under permissive speed travel of vehicle, said switch in closed circuit relation and actuated by movement of shoe coating with local contact for breaking the maintaining automatic brake control circuit to 95 cause service application of the brakes; an air actuated switch for open relation with manually operated handle to close said switch after application of the brakes, and manually operated permissive switch for 100 permissive entrance into an unclear block.

In testimony whereof, I have hereunto signed my name in the presence of two subscribing witnesses.

CLINTON F. SHADLE.
